CLAIM

We claim the ornamental design for a pedestal, as shown and described.

DESCRIPTION

FIG. 1 is a perspective view of a pedestal showing our new design;

FIG. 2 is another perspective view thereof, shown in another position of use;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a perspective view thereof, shown in another position of use;

FIG. 10 is another perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.

The dash-dot-dash broken lines adjacent shaded areas represent bounds of the claimed design. The even dash-dash broken lines adjacent shaded areas represent features of the pedestal and bounds of the claimed design and form no part of the claimed design. All other broken lines are directed to features of the pedestal that form no part of the claimed design.
